[57] CLAIM

The ornamental design for a combined ceiling fan support rod, motor housing and blade irons unit, as shown and described.

DESCRIPTION

FIG. 1 is a front-right-bottom perspective view of a combined ceiling fan support rod, motor housing and blade irons unit, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the combined ceiling fan support rod, motor housing and blade irons unit of my new design, on a reduced scale, with five fan blades and a rod respectively connected thereto, the broken line drawing of the fan blades and the rod is for illustrative purposes only and forms no part of the claimed design.
